UNITED STATES PATENT OFFICE.

WILLIAM F. BOSTOCK, OF BRAINTREE, MASSACHUSETTS.

ORNAMENTED SHOE UPPER.

Application filed December 2, 1921. Serial No. 519,378.

To all whom it may concern:

Be it known that I, WILLIAM F. BOSTOCK, a citizen of the United States, residing at Braintree, in the county of Norfolk and 5 State of Massachusetts, have invented new and useful Improvements in Ornamented Shoe Uppers, of which the following is a specification.

In the making of shoe uppers a practice 10 has developed of ornamenting them by inserting a piping in the seam overlap between certain parts of the upper, as, for instance, between the toe cap and the vamp, between the quarter and the vamp and elsewhere, or by inserting a tape in the seam so arranged that just its edge is visible. Such pipings, tape or the like are white or of some bright color contrasting with the color of the upper leather; but heretofore they 15 have been made of textile fabric and so are easily soiled. In fact, their designed decorative effect exists only when the shoe is new, for they absorb blacking, other dressings and dirt more readily than the leather 20 itself, and cannot be cleaned.

The object of this invention is to produce a decorative effect of similar nature but by means which are not subject to discoloration from the causes above noted, but are 25 even brightened and made more lustrous by the actions of cleaning and polishing the shoe uppers, and of which the decorative character is more pronounced and attractive than that of the piping heretofore used as 30 above mentioned.

This object is accomplished by applying to the exposed edges of the parts to be decorated an edging which is crimped or 35 squeezed upon the exposed edge of the said 40 part, or is so applied to a strip of leather or other material stitched into the adjacent seam, that only the edge so treated and ornamented edge is visible. Said edging may be applied in a continuous strip or in a 45 series of short strips or pieces placed end to end and fitted so closely together that the joints between them are not noticeable, or spaced apart, if desired or, if desired, the 50 ornamental edge may be given the appearance of a string of beads, either by suitably indenting the strips or strip sections, or by forming the applied pieces in the first place as beads slotted to embrace the edge of the leather piece and then clamp tight

to such edge. Such ornamentation may be 55 applied to any part of the upper, including the bounding edges thereof as well as the seam overlaps between the constituent parts of the upper.

In the drawings which illustrate the principles of this invention,—

Figure 1 is a perspective view of the toe 65 part of a shoe showing my improved ornamentation applied to the exposed edge of the toe cap.

Figure 2 is a fragmentary cross section 70 on an enlarged scale taken through that part of the upper to which the ornamentation is applied, and illustrating a step in the manufacture of a shoe so ornamented.

Figure 3 is a fragmentary longitudinal cross section of the upper showing the seam 75 between the toe cap and vamp with the ornamentation applied to the overlapping edge of the toe cap.

Figure 4 is a view similar to Figure 3 showing that modification of the invention which consists in attaching the ornamentation to a strip which is stitched into the seam 80 between the vamp and toe cap, or between other overlapping parts of the upper.

Figure 5 is a fragmentary side view 85 showing the application of the same character of ornamentation to the edge of a quarter in a blucher vamp shoe, illustrating also a modification of the invention adapted to situations where flexing of the ornamented part occurs in the ordinary mode of wearing the shoe.

Like reference characters designate the 90 same parts wherever they occur in all of the figures.

In Figures 1 and 2 *a* represents the fore 95 part of the vamp of a shoe upper and *b* represents the toe cap which is applied and stitched in any of the usual ways in the vamp. The joint between these parts is ornamented by a metal strip *c* which is so curved that it embraces the exposed edge 100 of the toe cap and is compressed upon the leather which it embraces so that it is secured by a gripping or clamping effect. In order to make the attachment of this applied edging material sufficiently secure, its under edge, which is hidden in the completed shoe upper, may be indented or cut 105 to form spurs, or more or less similar projections, which either penetrate into the

structure of the leather, or indent it so deeply that the accidental dislodgment of the edging is impossible. The outer or exposed edge of the edging is preferably curled over toward the grain surface of the leather, so that it indents this surface also and increases the security of attachment of the strip, while the raw edge of the metal is at the same time concealed.

10 In actual practice the strip so made and applied is so narrow that it appears to the eye as a narrow band or edging about one thirty-second of an inch in width. Its visible width may be greater or less than this, 15 but the figure given is that which is preferred in practice. The value of making the strip narrow is partly that its ornamental effect is greater, and partly that the stitches of the adjacent seam may be laid 20 close to the edge of the overlapping piece and the least possible opportunity given for this edge to be bent away from the surface of the vamp, and that a narrow width of the metal gives less opportunity for the 25 needle, used in stitching the inseam of the shoe to strike the applied strip and possibly be broken.

An upper ornamented in the manner above described is lasted in the ordinary 30 way, but after it has been pulled over and tacked, I preferably grind or burnish off the exposed part of the metal edging at the bottom of the shoe in order to diminish the amount of metal to be cut off by the inseam 35 trimming knife. The effect produced by such grinding is illustrated in Figure 2, where c' represents the outer part of the metal edging and c^2 the inner part which lies between the overlapping leather pieces. 40 Grinding away the edge part c' at the location of the inseam leaves only the part c^2 which needs to be cut off or may be struck by the inseam stitching needle.

It may be remarked, by the way, that in 45 Figure 2 I have shown only the toe cap in section, omitting the overlapping part of the vamp at this joint for clearness; and that in Figure 3 I have omitted to show the shoe lining.

50 By using for the edging sufficiently thin and ductile metal such as thin sheet copper, aluminum, silver, gold, or even soft iron, and by compressing the metal closely about the edge of the leather piece, it is possible 55 to bend the ornamental leather around the last without destroying the smooth continuity of the edging. However, it is within my contemplation to nick or notch the under edge part of the edging in order that 60 it may conform to the curvature of the shoe more readily; or I may make the edging in separate pieces placed more or less close together, instead of in a continuous strip.

65 The construction of edging in separate

pieces is illustrated in Figure 5, where also is illustrated the fact that other parts of the upper than the overlapping edge of the toe cap may be ornamented in the manner described. In the latter figure a represents 70 the vamp and d represents the forward part of the quarter of a shoe of the so-called blucher style, of which the ornamented edge is the lower overlapping edge of the quarter. In this case short metal sections e , essentially like the edging strip c , except that they are each of short length, are applied 75 so as to embrace and grip the edge of the leather in essentially the manner above described. These sections may be placed so closely together that the joints between them are not noticeable, whereby they give the appearance of a continuous but flexible strip; or spaces of any desired width may be left between them; or they may be made 80 with the appearance or form of beads so as to appear as an ornamental beaded edge. However, whatever may be their precise construction and appearance, they constitute 85 an ornamental edging which is flexible 90 and so conforms to the flexing of the leather with the motions of the foot on which the shoe is worn.

Figure 4 illustrates a modification in 95 which the metallic edging, instead of being applied directly upon the toe cap or other part of the upper, is applied to the edge of a strip f , which strip is inserted between the overlapping parts of the upper and is made fast by the seam which connects these 100 parts together. Such strip is ordinarily of leather, but may be fabric or other material, and the metal edging may be a continuous strip c or a series of sections like the sections e already described, according to 105 whether or not the inserted piece is placed in a location where it will be flexed when the shoe is worn.

Ornamentation of either of the characters hereinbefore described may be applied to 110 the overlapping edge of any part of the upper adjacent to any seam, or to the top edge of the upper or the edges of the lacing slit. The protection which I claim is not limited in that respect, but includes ornamentation of the character described applied to any part of a shoe upper which extends over or around a part of the foot on which the shoe is worn, in any of the ways hereinbefore described.

I may use for the purpose and in the manner described, any metal, as gold, silver, or base metals plated with gold or silver, copper, brass, aluminum, iron or soft steel; or nonmetals having the capability of being 115 applied in the manner described, while being free from the objectionable qualities of the pipings heretofore used.

A conspicuous advantage of the metal over the pipings and the like previously 120

used is that so far from the metal being soiled or discolored by shoe dressing and the ordinary effects of wear, it is actually rendered brighter and more lustrous by the 5 rubbing and brushing which are applied at such times. Shoe dressings not only do not adhere to the metal and are wiped off by the application of a brush or polishing cloth, but such effect as they have is that 10 of a detergent which cleans and enhances the luster of the edging. Nonmetals used for the purpose are such as have similar qualities to metal in these respects, that is, are not absorptive of or adherent to dressing and cleaning fluids or the stains and dirt of ordinary service. That form of the binding which consists of a continuous strip also has a mechanical advantage when applied to the edge of the toe cap, since it 20 adds to the stiffness of that part of the shoe and helps to maintain its shape.

What I claim and desire to secure by Letters Patent is:

1. A shoe upper including a number of 25 pieces stitched together in overlapping relationship, a flexible metallic edging at and

paralleling the seam and gripping the exposed edge of a part of said upper, said edging extending at least partly across the upper exposed to view and being sufficiently 30 flexible to permit flexing of the upper.

2. A shoe upper including a number of pieces stitched together with one of the contiguous pieces overlapping the adjacent piece at the seam, and a flexible metallic 35 edging embracing and clamping the exposed edge of such overlapping piece outside of the seam, said edging extending at least partly across the upper exposed to view, and being sufficiently flexible to permit flex- 40 ing of the upper.

3. A shoe upper comprising a flexible metallic edging sufficiently flexible to permit flexing of the upper, embracing and gripping the exposed edge of a part of the upper, said edging being exposed to view and extending across a part of the upper, which 45 extends over or around a part of the foot on which the shoe is worn.

In testimony whereof I have affixed my 50 signature.

WILLIAM F. BOSTOCK.
